DOCUMENT STACKER

Robert E. Edminster, St. Petersburg, Fla., assignor to International Business Machines Corporation, New York, N.Y., a corporation of New York

Filed June 4, 1957, Ser. No. 663,423

1 Claim. (Cl. 271—88)

This invention relates to a document stacker and more particularly a stacker in which the document is inverted and rotated ninety degrees from the direction of entry.

It is the principal object of this invention to provide an improved document stacker.

Another object of this invention is to provide a stacker which inverts and rotates each document.

A further object of this invention is to provide a stacker which stacks documents in the same order in which they are fed.

Other objects of the invention will be pointed out in the following description and claim and illustrated in the accompanying drawings, which disclose, by way of example, the principle of the invention and the best mode, which has been contemplated, of applying that principle.

In the drawings:

Fig. 1 is a sectional view of a stacker pocket taken along the line 1—1 in Fig. 2b.

Figs. 2a and 2b together form a front elevation of a machine including portions of several stacker pockets.

Fig. 3 is a plan view taken along the lines 3—3 in Fig. 2b.

The subject document stacker is shown and described in U.S. patent application Serial No. 631,925, filed December 31, 1956, on behalf of the instant applicant and others. Figs. 1, 2a, 2b and 3 correspond to Figs. 22, 1a, 1b and 23 respectively of the above cited application and corresponding reference numbers are used there and herein.

Only as much of the machine as is necessary to the understanding of the document stacker is shown and described herein. Reference may be made to the cited application for other details.

As described in the above cited application, the driven shaft 166, shown in Fig. 2a, provides the drive for the transport system for conveying checks from the drum unit 30 to the stacker unit 34, Fig. 2b. A drive pulley 583, Fig. 2a, is fixed to the shaft 166. Fifteen idler pulleys 584, Figs. 2a and 2b, are horizontally aligned with the driven pulley 583 and rotatably mounted on studs 586 fixed in the base plate 10. A flat transport belt 588 is mounted on the driven pulley 583 and the idler pulleys 584 and provides transporting means to the stacker unit 34. Opposite each idler pulley 584 is a pressure roller 590 rotatably mounted on a stud 592 fixed in a bracket 594 which is suspended by means of a leaf spring 596 and bolts 598 to members 690a and 691, shown in Figs. 1 and 3. A member 599 in Fig. 2a, extends into Fig. 2b, where it comprises only the lower flange 599a. Two rollers 600, Fig. 2a, mounted on brackets 601 fixed to a bar 602 which is mounted on the frame of the machine, are adjustable by mounting screws 603 to take up any slack which may exist in the belt 588. A roller 604, Fig. 2b, biased by a spring 605 is mounted in contact with the belt 588 to provide proper tension.

A check fed under the belt 588 from the belt 571, Fig. 2a, is advanced under a particular one of twelve

chute blades 612, Fig. 3, whereby the check is directed to a particular one of twelve pockets 36 associated with the particular chute blade. If none of the chute blades is selected, the check moves over the top of all chute blades and enters the thirteenth pocket 36—Reject.

Referring to Fig. 2a, the chute blade selecting mechanism, generally designated 32, is operated in the manner described in the hereinbefore cited application to feed a check under a selected chute blade 612.

Check stacker

Referring to Figs. 2a and 2b, when a check is fed past the selector unit 32 and under a selected chute blade 612, it advances toward the stacker pockets, designated from 15 left to right in Fig. 2b as 36—9, 36—8, 36—7, 36—6, 36—5, 36—4, 36—3, 36—2, 36—1, 36—0, 36—SS (Short Suppress), 36—MCS (Multiple Column Selection) and 36—Reject, to be directed into a particular pocket corresponding to the particular chute blade 612—9, 612—8, 612—7, 612—6, 612—5, 612—4, 612—3, 612—2, 612—1, 612—0, 612—SS, 612—MCS which was selected. Fig. 1 shows a sectional side elevation of the stacker unit, whereas Fig. 3 shows a plan view with successive portions broken away as you progress to the right. Referring to Fig. 2a, a plate 690 extends from the drum unit 30 past the selection unit 32 and terminates, in Fig. 2b, in a turned down portion 690a in the first pocket 36—9, which aids in rotating a check 90° as well as inverting the check, whereby the check is deposited on a platform 692. The succeeding pockets 25 have members 691 similar to the turned down end 690a of the member 690 which are fixed to a frame member 693 by nuts and bolts 694 as illustrated in Figs. 1 and 3. The plate 690, shown in Fig. 2a, has a turned down flange which adds strength to the plate and has holes, not 30 shown in Fig. 2a, through which the rollers 590 project to aid the belt 588 in transporting the checks. As described hereinbefore, the member 599 shown in Fig. 2a has an I-section for added strength which is reduced to the lower crossbar of the I-section as it progresses to the 35 right as shown in the sectional view, Fig. 1, where the reduced section is designated 599a. A curved guide member 695, best seen in Figs. 1 and 3, is mounted by means of brackets 696 and 698 to the base plate 10. Each chute blade 612, has a bifurcated end comprising a portion 612a and a portion 612b, Fig. 3. The portion 612b of each chute blade 612 is inserted through a hole 700 in the associated guide member 691. As a check is advanced toward the stacker pockets 36, the rear edge of the check is beneath a selected chute blade 612 which terminates at the pocket to which a check is being directed. As the check reaches the pocket, the leading edge is deflected by the end 612a of the chute blade into an opening between the members 690a and 695 or, in 40 pockets after the first pocket, between members 691 and 695. The check is curved downwardly by action of the members 690a—691 and 695 and toward the front of the machine whereby it is inverted and rotated 90° and is deposited on the platform 692. As shown in Fig. 3, each member 691 contains a pair of holes 706 through which the pressure rollers 590 cooperate with the belt 588 to 45 transport the checks.

The inverted checks are aligned by their momentum between the sidewalls of the pocket and against the front of the pocket; and as shown in Fig. 1, operate upon a lever 710 as described in the above cited application to actuate the air servomechanism to maintain the platform 692 at a level where the topmost check on the platform is sufficiently in contact with the lever 710 to maintain it in the position indicated as 710a.

While there have been shown and described and pointed out the fundamental novel features of the inven-

tion as applied to a preferred embodiment, it will be understood that various omissions and substitutions and changes in the form and details of the device illustrated and in its operation may be made by those skilled in the art without departing from the spirit of the invention. It is the intention therefore, to be limited only as indicated by the scope of the following claim.

What is claimed is:

Apparatus for receiving and stacking horizontally traveling horizontally positioned documents, comprising means forming a receptacle having vertical sides positioned below and extending substantially transversely to the direction of said horizontal travel, means for deflecting the leading edge of a said horizontally traveling document downwardly and into said receptacle, a twisted curved plate positioned to receive a said downwardly deflected leading edge of a traveling document and directing said leading edge first downwardly and thereafter horizontally into said receptacle substantially transversely of said first mentioned direction of horizontal travel, said document being inverted during travel into said receptacle, a vertically movable platform in said receptacle for receiving documents, successive documents being directed into said receptacle to form a stack, servo-responsive

support means for said platform, a pivotally mounted lever movable within a predefined range and having an operating end positioned adjacent said platform and an uppermost document of said stack for actuation by said documents, the degree of actuation being dependent upon the number of documents in said stack and the relative position of said platform with respect to said lever, and servo means actuated in response to the movement of said lever through a preselected portion of said predefined range for operating said support means to maintain said uppermost document of said stack at a desired constant level with respect to said deflecting means and said curved plate.
